UNITED STATES PATENT OFFICE.

EDWARD CRAIG, OF ST. JOSEPH, MICHIGAN.

BOX-SEALING MACHINE.

Application filed February 27, 1918, Serial No. 219,410. Renewed July 31, 1922. Serial No. 578,850.

To all whom it may concern:

Be it known that I, EDWARD CRAIG, a citizen of the United States of America, and resident of St. Joseph, county of Berrien, and 5 State of Michigan, have invented a certain new and useful Improvement in Box-Sealing Machines, of which the following is a specification.

This invention relates to stapling machines in general, but more particularly to 10 those of the old and well known type in which an arm projects outwardly to support the work, the end of the arm being provided with a clinch-block or anvil directly 15 below the stapler, whereby various kinds of work can be fastened together by resting the materials on the arm below the stapler, said arm being of any suitable or desired size or proportions, depending, of course, upon the 20 character of the work.

Generally stated, the object of the invention is to provide a novel and improved 25 stapling machine of the foregoing general character, having improved means for supporting the work in position to receive the staples.

Special objects are to provide an improved arrangement and construction of the work-supporting arm below the stapler; to provide 30 novel and improved means for supporting the work below said arm; to provide an improved construction and arrangement whereby the machine can be employed for sealing the bottom of a carton or box, 35 preparatory to filling the same, as well as for sealing the top after the box is filled.

It is also an object to provide certain details and features of construction and combinations tending to increase the general efficiency and desirability of a box-sealing- 40 stapler of this particular character.

To the foregoing and other useful ends, the invention consists in matters hereinafter set forth and claimed, and shown in the accompanying drawings, in which:—

Figure 1 is a side elevation of a stapling-machine embodying the principles of the invention.

Figure 2 is a perspective of a box or carton 50 after the top thereof is sealed, showing the work-supporting arm just after it has been withdrawn from the top of the box.

Figure 3 illustrates a step in the operation of sealing the bottom of the box.

Figure 4 is an enlarged horizontal section 55 on line 4—4 in Figure 1.

Figure 5 is an enlarged horizontal section 60 on line 5—5 in Figure 1.

Figure 6 is an enlarged detail section on line 6—6 in Figure 5.

Figure 7 is a plan view of one of the ball bearings involving the construction of the table shown in Figures 5 and 6.

As thus illustrated, the invention comprises a body or standard 1 having a base 65 2 and an upper horizontally disposed arm 3, the stapler 4, of any suitable character, being disposed at the outer end of this arm and operated by a belt on the pulley 5 at the back of the machine. The work-sup- 70 porting arm 6 is of any suitable material, such as steel, and is pivoted at 7 to swing up and down about a horizontal axis, this pivot being located on the standard 1 a short distance below the arm 3, so that the 75 arm extends outward immediately below the stapler. The outer end of the arm 6 is preferably provided with a clinch-block or anvil 8, of any suitable character, for clinching the staples in the usual and well known manner.

A rod 9 has its upper end pivoted at 10 on the bottom of the arm 3, and extends downward through a slot 11 in the arm 6, being provided with a shoulder 12 which rests upon the top of said arm. The lower portion of this arm 9 is threaded and provided with a thumb-nut 13, and a spring 14 is interposed between this thumb-nut and the bottom of this arm 6 whereby the latter is yieldingly supported. The 80 thumb-nut 13 is adjusted until the spring 14 is compressed to the desired degree or extent, so that the arm 6 is held against the bottom of the shoulder 12, and in this position the arm 6 is just the right distance from the stapler for materials of minimum thickness, but thicker materials can be used, of course, inasmuch as the extra or additional thickness is compensated for by the yield- 85 ing action of the spring 14, the greater thickness causing the outer end of the arm 6 to be slightly depressed when the staples are driven.

Thus the arm 6 is preferably rigid or non-flexible, but is pivoted at 7 to swing downward, and is yieldingly supported by the spring 14, so that the arm is not rigidly supported, nor is it necessarily of flexible material as the pivotal mounting allows the 90 95 100

arm when constructed of rigid material to accommodate itself to various thicknesses of work.

A table 15 is disposed below the arm 6, this table 15 being provided with apertures for the balls 16, which latter extend a slight distance above the top of the table, so that the bottom of the box, when supported on the table 15, will slide around readily, thereby permitting easy and complete manipulation of the box during the operation of the sealing of the top thereof after the box is filled. The balls 16 can be supported by smaller balls 17 held in cups 18, but it will be understood this antifriction arrangement can be changed or varied to suit the requirements, and that any suitable arrangement can be employed for this purpose. The table 15 is rigidly mounted on the upper end of a vertically disposed rack 19, the teeth of which latter engage the segmental pinion 20, the latter being mounted with its axis 21 disposed transversely of the horizontally extending arm 22 which is swingingly mounted on a slide or traveler 23 arranged to slide up and down on the guideway 24 of the standard 1, whereby the arm 22 can be raised and lowered. The axis 21 of the segmental pinion 20 can be operated by a removable handle 25, to raise and lower the rack 19, thereby to raise and lower the table 15 for boxes of different sizes. A bell-crank-lever 26 is pivoted at 27 on the bottom of the table 15, and has its vertically disposed lower portion 28 provided with a plurality of adjustable dogs 29 adapted to engage the transverse pin 30 on the outer end of the arm 22, whereby the table 15 can be raised or lowered by the rack and pinion mechanism and one of the dogs 29 can then be adjusted into position to properly engage the pin 30 and thus hold the table at the desired height. The handle 31 of the bell-crank-lever 26 can be raised to disengage the dog 29 from the pin 30, and by providing a plurality of dogs, set at different positions, for boxes of different heights, the table can be quickly adjusted up or down and held in the desired position. In this way, therefore, quick adjustment is afforded for different sizes of boxes, in a manner that will be readily understood.

As previously stated, the arm 22 is swingingly mounted on the slide or traveler 23, and this is preferably accomplished by providing a vertically disposed screw 32 having its upper and lower ends mounted in brackets 33 on the standard 1, whereby this screw is held vertically. It will be seen that this screw 32 is disposed at one side of the slide or traveler 23, and forms the pivot about which the arm 22 swings in a horizontal plane. At its other side, this arm is provided with an interlocking connection 34, so that this side of the arm will inter-

lock with the slide or traveler 23, and a removable pin 35 is inserted into said connection 34 thereby to lock the arm 22 against lateral swinging movement. When the pin 35 is pulled upwardly out of the connection 34, the latter will then separate and allow the arm 22 to swing around until the table 15 is out of the way. To raise and lower the slide 23 on the screw 32, the latter is preferably provided with a screw-threaded bevel-gear 36 which engages the bevel-pinion 37 on the obliquely arranged shaft 38, which latter is supported for rotation in the bearing 39 on the arm 22, being provided at its outer end with a crank-handle 40 for the operation thereof. With this arrangement, and by grasping the handle 40 and rotating the shaft 38, the bevel-pinion 37 will be rotated, and this will rotate the bevel 36 on the screw 32, and the latter will move the arm 22 up or down, depending upon the direction in which the crank-handle 40 is operated. This screw 32 can be rigidly held at its upper and lower ends in the brackets 33, and the bevel-gear 36 can be threaded to operate like a nut on the screw 32, thereby to raise and lower the arm 22 when the crank-handle is operated, in the manner stated. The screw 32 serves as the means by which to raise and lower the table 15 to obtain accurate adjustment, and serves also as the vertical pivot about which the arm 22 and the table 15 may swing laterally.

A machine of this kind can be used, of course, for various purposes. For example, the box or carton shown in Figures 2 and 3 can be sealed at its top, after being filled, in the following manner:—First, the filled box can be placed on the table 15 below the arm 6, and two arms or flaps can be folded upon each other, and upon the arm 6, and then stapled together. Then the box is removed and turned around and the operation repeated with the other flaps of the top, thus sealing the top of the box.

Furthermore, when the table 15 is swung out of the way, a standard 41, having a clinch-block 42 at its upper end, can be mounted on a pivot 43 at its lower end, on the base 2, directly below the stapler, and held in position in any suitable or desired manner, whereby the bottom flaps of the box can be stapled together before the box is filled. This is done by tilting the standard 41 outward, and slipping the box upside down over the upper end thereof, and by then allowing the standard 41 to tilt back into position under the pull of the spring 44, until the adjustable stop 45 holds it in the desired position. Then the box is manipulated on the clinch-block 42, below the stapler, and the bottom flaps of the box are stapled together. Of course, the bottom flaps of the box could be stapled together 130

on the arm or table 6, but when stapled together on the head or clinch-block 42, in the manner described, all four flaps of the bottom will be stapled together, the second 5 row of staples extending through all the flaps. However, the boxes can all be passed through the machine, to close the bottoms thereof, on the clinch-block 42, and then the boxes can all be filled. Then the standard 10 41 can be removed, and the table 15 can be swung back into place below the stapler, and in addition the arm 6 can be swung upward into position, it being understood that when the standard 41 and the clinch- 15 block 42 are used this arm 6 is released by removing the thumb-nut 13 and allowing it to tilt downward out of the way; but, after the boxes are filled, and when it is desired to seal the tops thereof, the arm 6 can then 20 be swung upward and the spring 14 and the thumb-nut 13 restored to their operative positions, thereby to yieldingly support this arm or table in position to support the top flaps of the box below the stapler. 25 It will be seen, therefore, that the invention does not relate to the stapler, but resides in the means and devices for supporting the work below the stapler. The boxes shown in Figures 2 and 3 can be made of 30 paste-board, or paper, or fiber-board through which the staples are easily driven. It is obvious, however, that other boxes, made of wood or veneer, can be fastened together, either partially or entirely, on the machine shown and described, and the size and proportions of the machine, and the length and breadth and thickness of the arm 6, will, of course, depend largely upon the kind of boxes and materials and the 40 character of the work to be stapled together or sealed.

It will be seen that the bevel gearing 36 and 37 forms a slow-acting means for raising and lowering the work table, while the 45 rack and pinion 19 and 20 form a quick-acting means for raising and lowering the work table or work support, whereby proper up and down adjustment of the table can always be obtained in a satisfactory manner. 50 The elements 29 are formed like ratchet teeth, it will be seen, to slide upwardly over stop 30, but they are adapted to catch on this stop and prevent the table from moving downward. The work supporting means 55 thus provided are suited to varying conditions and serve to adapt the machine for use in sealing boxes of various shapes and sizes.

What I claim as my invention is:—

60 1. In a stapling machine, the combination of an overhanging stapler, a work-supporting table in the form of an arm pivoted to swing up and down and extending outward below said stapler, with a clear 65 space below said arm, and stationary means

having a spring thereon to yieldingly support said arm in normal position below said stapler, so that the pressure of the stapler on thick material will press the arm downward.

70

2. A structure as specified in claim 1, in which said means comprises a transverse pivot for said arm, a depending support extending downward through said arm, a spring on said support to engage the bottom of the arm, a stop on said support to limit the upward movement of the arm, and means to regulate the tension of said spring.

75

3. In a stapling machine, the combination of an overhanging stapler, a work-supporting table below said stapler, a supporting arm below said table, a rack and pinion to raise and lower the table on said arm, a catch serving as a locking device operating independently of said rack and pinion to hold the table in adjusted position after the operation of said rack and pinion, and means to manually control said clutch at will.

80

4. A structure as specified in claim 3, in which said locking device comprises a bell-crank-lever pivoted underneath said table and provided with one or more adjustable dogs, and means on the end of said arm to engage said dog or dogs.

85

5. A structure as specified in claim 3, in combination with screw mechanism to raise and lower said arm.

90

6. A structure as specified in claim 3, in combination with means to allow said arm to swing laterally to permit said table to swing out of the way when it is desired to use another form of support below the stapler.

95

7. In a stapling-machine, the combination of an overhanging stapler, a work-supporting table below the stapler, an arm to support said table, and screw mechanism to support said arm for adjustment up and down, said mechanism including a vertically disposed screw held against rotation and having a bevel-gear thereon, said bevel gear being threaded to operate like a nut on said screw, a horizontally disposed shaft on said arm, a bevel pinion on said shaft to engage said bevel-gear on the screw, and a crank-handle to operate said shaft.

100

8. A structure as specified in claim 7, in combination with means to permit said arm to swing laterally about said screw as a vertical pivot, and means to lock said arm against lateral swinging movement.

105

9. A structure as specified in claim 7, in combination with means to raise and lower the table on the outer end of said arm, and to hold the table in adjusted position thereon.

110

10. In a stapling machine, a stapler, a work-supporting table below said stapler, a supporting arm for said table, and mecha-

115

120

125

- nism for raising and lowering said arm, having provisions to permit lateral movement of the arm about a vertical axis, and to hold the arm in any raised or lowered position thereof.
11. A structure as specified in claim 10, in combination with devices for adjusting said table up and down on the end of said arm.
- 10 12. A structure as specified in claim 10, in combination with work-supporting means to be placed in position below the stapler when said table is swung to one side.
- 15 13. In a stapling machine, the combination of an overhanging stapler, a work-supporting table below the stapler, an arm to support said table, and screw mechanism to support said arm for adjustment up and down, said mechanism including a vertically disposed screw having a bevel-gear thereon, a horizontally disposed shaft on said arm, a bevel pinion on said shaft to engage said bevel-gear on the screw, and a crank-handle to operate said shaft, together with means whereby said arm swings laterally about said screw as a vertical pivot, and means to lock said arm against lateral swinging movement.
- 20 14. In a stapling machine, the combination of an overhanging stapler, a work-supporting table below the stapler, an arm to support said table, and screw mechanism to support said arm for adjusting up and down, said mechanism including a vertically disposed screw having a bevel-gear thereon, a horizontally disposed shaft on said arm, a bevel pinion on said shaft to engage said bevel-gear on the screw, and a crank-handle to operate said shaft, in combination with means to raise and lower the table on the outer end of said arm, and to hold the table in adjusted position thereon.
- 25 15. In a stapling machine, the combination of a work support, quick acting means operative at will for raising and lowering said support, and slow-acting means operative at will for raising and lowering said quick-acting means and said work support, said quick-acting means comprising a rack and pinion, and said slow-acting means comprising a vertically disposed screw forming a support for said rack and pinion.
- 30 16. In a stapling machine, the combination of a work support, quick-acting means operative at will for raising and lowering said support, and slow-acting means operative at will about a vertical axis for raising and lowering said quick-acting means and said work support, said quick-acting means being supported by said slow-acting means for horizontal swinging movement about said axis.
- 35 17. In a stapling machine, the combination of a work support, quick-acting means operative at will for raising and lowering said support, and slow-acting means operative at will for raising and lowering said quick-acting means and said work support, in combination with adjustable means cooperating with said quick-acting means to determine the position of said support.
- 40 18. In a machine of the class described, the combination of a vertically adjustable work support, a pivoted member depending from said support, a plurality of elements on said member, means whereby said elements are adjustable up and down and toward and away from each other on said member, and a stop for engaging any one of said elements to support the work holder in its raised or lowered position.
- 45 19. A structure as specified in claim 18, in combination with a rack and pinion for quickly raising the work support, and permitting the support to fall by gravity when the element in use is disengaged from said stop.
- 50 20. A structure as specified in claim 18, in which said elements are formed to slide upwardly like ratchet teeth over said stop, and are adapted to engage said stop to prevent downward displacement of the work support.
- 55 21. In a machine of the class described, the combination of a vertically disposed screw, means for supporting said screw in fixed position, so that the screw is held against endwise and rotary movement, a bevel gear having screw threaded engagement with said screw, a work support sustained in raised position by said bevel gear, and a pinion for rotating said bevel gear to raise and lower the work support.
- 60 22. A structure as specified in claim 21, in combination with means whereby said work support swings horizontally about the vertical axis formed by said screw.
- 65 23. A structure as specified in claim 21, in combination with quick-acting means for raising and lowering the work support without disturbing said bevel gearing.
- 70 24. In a stapling machine for sealing filled boxes provided with sealing flaps, the combination of a thin arm for insertion under the flaps to provide an anvil for the clinching of the staples, and devices for permitting said arm to move downward without flexing under the pressure of the stapler.
- 75 25. A structure as specified in claim 24, in which said devices include a spring to yieldingly hold the arm in position against the pressure of the stapler, the arm being mounted to tilt downward at its outer end against the tension of said spring, thereby to allow for flaps of different thicknesses.
- 80 26. A structure as specified in claim 24, in which said devices comprise a pivotal support for the arm, a spring to support the

arm against downward movement about said pivot, and means for adjusting the tension of said spring.

27. In a stapling machine for sealing filled boxes having sealing flaps, a thin arm for insertion under the flaps to provide an anvil for clinching the staples, a pivot (7) for supporting said arm, a rod (9) supported at its upper end by a pivot (10) and 10 extending through a slot (11) in the arm, having a stop (12) to limit the upward movement of the arm, a spring (14) on said rod to yieldingly support said arm against downward movement, and a nut (13) on 15 the lower end portion of said rod to regulate the tension of said spring.

28. In a box sealing machine, the combina-

tion of a flattened non-flexible member for insertion under the flaps of the box, after the flaps are folded upon the top of the box, 20 so that said member may be inserted between the contents and the flaps after the box is filled, means to support said member with a clear space below its outer end portion, and a stapler disposed over said 25 member to insert staples through the flaps, said member having means for clinching the staples, having spring means whereby said flattened member, although non-flexible, may yield and move downward under 30 the pressure of the stapler.

Signed by me at St. Joseph, Michigan,
this 20th day of February, 1918.

EDWARD CRAIG.
